A. S. HOVANDER

POWER HAMMER

Filed Jan. 11, 1924

INVENTOR
August S. Hovander
Harry Bowen
ATTORNEY

UNITED STATES PATENT OFFICE.

AUGUST S. HOVANDER, OF BURLINGTON, WASHINGTON.

POWER HAMMER.

Application filed January 11, 1924. Serial No. 685,546.

To all whom it may concern:

Be it known that I, AUGUST S. HOVANDER, a subject of the King of Sweden, residing at Burlington, in the county of Skagit and State of Washington, have invented a new and useful Power Hammer; and I do hereby declare that the following is a full, clear, and exact specification, such as will enable others skilled in the art to which it appertains to make and use the same.

The invention is a power hammer in which the head will travel in a vertical plane so that the striking surface of the head will be parallel to the surface of the anvil when it engages the anvil or material on the anvil and in which the head is operated by an eccentric through a spring.

The object of the invention is to provide a power hammer in which the striking surface of the hammer will be in a horizontal position as it delivers a blow.

Another object of the invention is to provide a power hammer in which the hammer is operated by an eccentric through a spring member.

And a further object of the invention is to provide a power hammer with a belt shifter and a brake operated by a common lever so that the movement of the hammer may be retarded or positively controlled.

With these ends in view the invention embodies a power hammer having the head supported from a suitable frame by a double connection with four pivot points; a yoke for connecting one of the supporting members to an eccentric on a shaft having a tight and loose pulley and also a brake, a means for shifting the belt on the pulley and for operating the brake, and an anvil at the forward end of the machine.

Other features and advantages of the invention will be seen from the following description taken in connection with the drawings, wherein:—

Figure 1 is a side view.

Figure 2 is a front view.

Figure 3 is a rear view.

Figure 4 is a section showing the brake.

In the drawings I have shown my device as it would be constructed wherein numeral 1 indicates the hammer head which is supported on a spring member 2 and a rod 3. The head is provided with openings 4, 5, and 6 through which the supporting member may be attached to it by pins 7 and 8. It will be seen that by attaching the spring

member 2 to the opening 4, and the rod 3 to the opening 5 as shown, the flat surface of the hammer head will be in the downward position as shown, and by reversing the head and attaching the rod 3 to the head through the opening 6, the rounded end 10 of the head may be placed in the downward position.

The spring member 2 may be constructed with a long flat piece of spring steel 11 through its center one end of which may be attached to the pin 4 and the other may extend to the point 12 at the rear of the machine. Other flat pieces of spring steel 13 and 14 may be placed on each side of the member 11 and their forward ends connected by a ring 15 as shown in Figure 1. The ends of these members may extend practically to the edges of the hammer 1 so that the member 11 will be supported for substantially its entire length. Other flat pieces of spring steel 16 and 17 may be placed on the outside of the members 13 and 14 and the ends of these members held together by a ring 18 and extending from the point 12 at the rear of the machine to a point 19 a short distance from the head 1. And other flat pieces of spring steel 20 and 21 may be placed on the outside of the members 16 and 17 and their ends held together by a ring 22 and extending from points 12 to a point 23 a short distance from the ring 18. These members will form a leaf spring which will be held in a clamp 24 and pivoted to a plate 25 by pins 26 in the sides.

The rod 3 will be provided with eyes 27 and 28 at each end, one of which will be pivotally mounted on the pin 8 in the head 95 and the other pivotally mounted between the plates 25 on a pin 29. At the rear of the spring is a sliding member 30 which may be held to the spring by a set screw 31 and in this member is a pin 32 upon which a yoke 33, which extends downward, is pivotally mounted. The lower end of the yoke 33 is provided with an eye or bearing 34 which is pivotally attached to an off-set 35 of a shaft 36 which is pivotally mounted in bearings 37 and 38 of the main frame. The shaft 36 extends through the bearings on one side and on this extended end is a tight pulley 39 and a loose pulley 40 over which a belt 41 will pass. On the opposite end of the shaft 36 is a pulley or drum 42 over which a metal band 43, the

lower ends of which are attached to a rod 44 as shown in Figure 4, may pass to form a brake. It will be seen that as the band 43 is drawn downward it will frictionally grip the pulley or drum 42 and thereby retard or stop the motion of the hammer. A collar 45 may be placed on the shaft 36 which will engage the side of the bearing 38 and prevent the shaft moving in that direction. A U bar 46 will extend from the forward end of the machine to the rear on both sides and each side will be pivoted to the frame on pins 47. One leg of this member will form the rod 44 to which the brake band 43 is attached as shown in Figures 3 and 4 and on the outer end of this section is a weight 48, which may be adjustably held to it by a set screw 49. It will be seen that this weight will hold the forward end of the bar upward and pull the brake downward to stop the machine as soon as the forward end of the member 46 is released. The opposite side of the member 46, which I have indicated by the numeral 50, will extend along the opposite side and engage a slotted opening 51 in a lever 52 which is pivotally mounted on a support 53 by a pin 54. The opposite end of the lever is provided with a U frame 55 through which the belt 41 may pass and by which the belt may be shifted from one pulley to the other as may be desired. It will be observed that the U frame 55 will engage both sides of the belt at both edges.

The main frame may be constructed with two inverted U-shaped members 56 and 57 and a supporting member 58 as shown. These members may be tied together by suitable cross bars and attached to any suitable base or foundation.

At the forward end of the machine is an anvil 59 which may be constructed with a piece of pipe or tubing 60 having a flange 61 at its lower end and its upper end squared, and a rectangular shaped piece of hard steel or other suitable material 62 which may be placed inside of the member 60.

It will be understood that changes may be made in the construction without departing from the spirit of the invention. One of which changes may be in the design, shape or proportion of any of the members, another may be in the type of anvil used, another may be in the design of the main frame, another may be in the type of eccentric, another may be in the use of a brake of a different design, and still another may be in the use of any suitable motive power instead of the belt and pulleys as shown.

The construction will be readily understood from the foregoing description. To use the device it may be assembled as shown in Figure 1 and it will be seen that as power is applied, or the eccentric rotated, the hammer head will move upward and downward in a vertical plane, and as it moves downward the spring member 2 will first permit it to drag slightly behind and then bring it down with a quick hard blow. The rings 15, 18, and 22 will protect the spring member 2 and prevent its breaking or bending with the rebound. It will be seen that the length of stroke may be adjusted by sliding the member 30 backward or forward on the spring member or by placing the pin 32 through different holes in the end of the yoke 33.

Having thus fully described the invention, what I claim as new and desire to secure by Letters Patent, is:—

1. A power hammer having a head, a spring member pivotally attached to said head, a frame in which said spring member is pivotally mounted; a bar also pivotally attached to the hammer head at a point directly above the point at which the head is attached to the spring member, and its other end pivotally mounted in the frame in which the spring member is mounted at a point directly above the pivot point of the spring member; and a suitable means that may be attached to the rear end of the spring member for moving the hammer upward and downward.

2. A power hammer having an anvil; a head directly above the anvil; a spring member constructed of a flat piece of material with one long piece forming a central member and other pieces of different lengths on the sides of the central member, said latter members having rings for tying their free ends together; a socket for pivotally holding the spring member in the frame; a bar parallel to the spring member, one end of which is pivotally attached to the frame at a point above the pivot point of the spring member, and the other end of which is pivotally attached to the head at a point above the point at which the spring member is attached to the head; a socket adjustably held to the rear end of the spring member; a yoke pivotally attached to the socket at its upper end; an eccentric on which the yoke is pivotally mounted; means for rotating the eccentric; a brake for holding the eccentric; and a common means by which the brake and means for rotating the eccentric may be operated simultaneously.

AUGUST S. HOVANDER.
